UNITED STATES PATENT OFFICE

1,979,891

CUTTER DEVICE

Tideman M. Lilleberg, Chicago, Ill., assignor to
 The Nye Tool & Machine Works, Chicago, Ill.,
 a corporation of Illinois

Application April 21, 1933, Serial No. 667,277

6 Claims. (Cl. 81—192)

My invention relates more particularly to the cutter elements of cutter devices, as for example and especially so-called pipe cutters for cutting off metal pipe; and my primary object is to provide improvements in such devices to the end of reducing the cost of manufacture thereof.

Referring to the accompanying drawing:

Figure 1 is a view in side elevation of a cutter device having cutter elements constructed in accordance with my invention.

Figure 2 is an end view of similar cutter elements.

Figure 3 is a sectional view taken at the irregular line 3—3 on Fig. 2 and viewed in the direction of the arrows; and

Figure 4, a view like Fig. 3 of a modification of the cutter element.

I have chosen to illustrate my invention as embodied in a so-called pipe cutter of a well known type and comprising a body portion 5 presenting at one end a tubular extension 6 internally threaded, and at its opposite end a lateral extension 7 containing recesses 8.

Extending into the recesses 8 and journaled on shafts 9 mounted in the side walls of these recesses are rotary cutter elements 10 constructed in accordance with my invention and located at opposite sides of the longitudinal axis of the extension 6.

The device also comprises a rotatable cutter element 11, also embodying my invention, mounted on a shaft 12 in a recess 13 in a block 14 pivotally mounted on the body portion 5, the mounting of the cutter element 11 being such, as shown, that it extends at the side of the pipe to be cut and represented at 15 opposite that at which the cutter elements 10 extend.

Pressure is applied for producing the cutting of the pipe by the cutters 10 and 11 by a rotatable shaft 16 mounted at its threaded portion 17 in the thread of the tubular extension 6, the inner end of the shaft 16 bearing against an end of the block 14.

The cutter elements 10 and 11 which are alike in construction, each comprise, according to the showing in Fig. 3, a relatively thin cutter disk 18 of metal adapted to be tempered, centrally apertured as represented at 19 and flanged at the opening 19 at the opposite faces of the disk 18, as represented at 20 and 21, respectively, to provide a relatively broad annular bearing surface at which to support the disk.

The support for the cutter disk and which forms a bushing therefor comprises a tubular member 22 provided for journal mounting on the support-

ing shaft 9 or 12, as the case may be, and extending through the central opening 19 in the cutter disk, one end of the tubular member 22 having an enlargement 23 opposing a face of the cutter disk and containing an annular recess 24 into which the flange 20 on the disk 18, extends.

The support for the cutter disk also comprises a member 25 mounted on the tubular member 22 to oppose the opposite face of the cutter disk 18 and containing an annular recess 26 to receive the flange 21 on the disk 18.

The cutter disk 18 and the parts of the support therefor and above described are preferably firmly and rigidly secured together with the enlargement 23 of the member 22 and the member 25 firmly clamped against the opposite faces of the cutter disk 18 beyond the flanges 20 and 21 as shown. Any suitable means for this purpose may be provided, but by preference these parts are held together as stated by deflecting the metal of one of the members forming the support into interlocking relationship to the other of said members as for example and preferably as shown, namely, by reaming the outer end of the member 25, as represented at 27, and swaging the adjacent end of the tubular member 22 into the space thus provided as represented at 28.

Referring to the modification shown in Fig. 4, the cutter disk is of the same construction as the disk 18 and is similarly indicated, the only difference between these constructions being in the construction of the support for the cutter disk.

In the construction shown in Fig. 4 the support for the cutter disk is shown as formed of two sections 29 and 30, the section 29 comprising a tubular portion 31 at which the support is adapted to be rotatably supported, and an outer flange portion 32 at one end spaced from the portion 31 to provide an inwardly opening recess 33, and the section 30 comprising a tubular portion 34 telescoped with the tubular portion 31 and having at the end thereof opposite that at which the flange 32 is provided, an outer flange portion 35 spaced from the tubular portion 34 to provide an inwardly opening recess 36.

The cutter disk 18 surrounds the tubular structure formed of the portions 31 and 34 and is engaged at its opposite faces by the adjacent ends of the flanges 32 and 35 preferably in clamped relation, with the flanges 20 and 21 on the cutter disk 18 extending into the recesses 33 and 36, respectively.

The parts referred to are held together in any suitable way, as for example and preferably by

swaging the metal of the tubular portion 31 outwardly as represented at 37, into interlocking relation with the adjacent receding edge 38 of the section 30.

- 5 As will be understood from the foregoing, the provision of the broad bearing surface provided on the cutter disk at the opening therein permits of the forming of the disk-support of relatively soft metal with no heat treatment required 10 and without danger of the cutting of the cutter disk into the portion of the support on which this disk is mounted, the construction shown in Fig. 3 permitting of the forming of the disk support of relatively soft metal, as for example low 15 carbon steel, on a screw machine, and the construction shown in Fig. 4 permitting the sections to be formed from relatively soft sheet metal strips on a punch press.

The provision of portions of the disk support 20 at opposite faces of the cutter disk beyond the flanges 20 and 21 of the latter serve as a backing for the cutter disk holding the latter against distortion and thus permitting of the provision of the cutter disk as a relatively thin member.

25 While I have illustrated and described certain particular constructions constituting embodiments of my invention, I do not wish to be understood as intending to limit it thereto as the same may be variously modified and altered and 30 the invention embodied in other forms of structure, without departing from the spirit of my invention.

What I claim as new and desire to secure by Letters Patent, is:

- 35 1. A cutter device comprising a thin cutter disk containing an opening, said disk comprising a face portion and a flanged portion, said flanged portion being disposed about said opening to provide an extended bearing surface, and a sectional support for said disk having an apertured portion extending through the opening in said disk and portions disposed at opposite faces of said disk and extending outwardly beyond the plane of said flanged portion, said support containing a recess to receive said flanged portion. 40 2. A cutter device comprising an apertured support having a circumferential channel in its periphery and an overhanging part about said channel, and a thin cutter disk rotatable with the support having an opening, the material of 45 said disk being thickened to form an extended bearing surface, said thickened portion seating in said channel.

3. A cutter device comprising a thin cutter disk having an opening, a tubular support initially separate from the disk, said tubular support being rotatable with the disk and extending through said opening, and an enlargement on the exterior of said support integral therewith against which one side of the disk abuts at a distance outwardly of said opening, and an annular member opposed to said enlargement telescoped over and fastened to said support and abutting the side of the disk opposite the said enlargement, said disk being thickened about said opening to increase the area of contact of the disk with said support, said enlargement and annular member being spaced from the sides of the disk between said opening and their zones of abutment with the disk.

4. A cutter device comprising a cutter disk having an opening, a support therefor initially separate therefrom, said support being rotatable with said disk and comprising sections having tubular portions in telescoped relation, said tubular portions passing through said opening and the outer tubular portion seating said disk, and inwardly extending tubular portions rigid with 100 and of greater diameter than the first mentioned tubular portions, said inwardly extending tubular portions engaging opposite sides of the disk in spaced relation to the first mentioned portions.

5. A cutter device comprising a cutter disk having an opening, an apertured support of soft metal rotatable with the disk and passing through said opening, said disk throughout the major portion thereof being of a thickness liable 110 to cut into the support in the use of the device, and said disk about said opening being thickened to extend that surface of the disk in bearing engagement with said support to prevent cutting of the latter by the disk.

6. A cutter device comprising a cutter disk having an opening, an apertured support of low carbon steel rotatable with the disk and passing through said opening, said disk throughout the major portion thereof being of a thickness liable 120 to cut into the support in the use of the device, and said disk about said opening being thickened to extend that surface of the disk in bearing engagement with said support to prevent cutting of the latter by the disk.
